UNITED STATES PATENT OFFICE.

HERMAN C. MUELLER, OF FOND DU LAC, WISCONSIN.

JUMP-SPARK APPARATUS.

SPECIFICATION forming part of Letters Patent No. 793,143, dated June 27, 1905.

Application filed August 27, 1904. Serial No. 222,388.

To all whom it may concern:

Be it known that I, HERMAN C. MUELLER, a citizen of the United States, residing at Fond du Lac, in the county of Fond du Lac and State 5 of Wisconsin, have invented certain new and useful Improvements in Jump-Spark Apparatus, of which the following is a specification, reference being had to the accompanying drawings, forming a part thereof.

10 My invention relates to jump-spark apparatus for ignition purposes in gas-engines and the like. Its main objects are to provide an apparatus for this purpose insuring more certain and effective operation and which may 15 be more economically constructed than has hitherto been possible with coils of the ordinary construction.

It consists in certain novel features of construction and arrangement of parts herein- 20 after particularly described, and pointed out in the claims.

In the accompanying drawings like letters designate the same parts in the several figures. Figure 1 is a vertical longitudinal section 25 of my invention on line 1 1, Fig. 2. Fig. 2 is a horizontal section of the same on line 2 2, Fig. 1. Fig. 3 is an end view from the right with reference to Figs. 1 and 2. Fig. 4 is a cross-section on line 4 4, Fig. 2; and Fig. 5 30 is a diagram of my invention, showing the relation of the parts and the electrical connections.

A body or casing *a* serves as a container 35 for a pair of separately-mounted parallel induction-coils *b* and *b'*, together with a condenser *c* of the ordinary type. The coils and condenser are preferably embedded in and separated by a body of non-conducting material *d*, such as beeswax or paraffin, although 40 other means, such as a sheet of glass or rubber, may be used to separate the coils and condenser.

Referring to Fig. 2, it will be seen that the induction-coils *b* and *b'* are provided with separate or individual cores *g* and *g'* of the usual type, which extend somewhat beyond both the primary and secondary windings at either end and at one end project slightly through the casing. To prevent possible movement 50 of the coils in the casing, it is sometimes de-

sirable to connect the other ends of the cores with a yoke of wood or other non-conducting material. (Not shown.) About the cores are the primary windings *h* and *h'* and secondary windings *i* and *i'*, insulated from each other and the cores in any suitable manner. As shown in the drawings, the primary of one induction-coil is wound to the right and the primary of the other to the left, (although in practice the winding may be varied,) their terminals at one end being directly connected. What might be termed a "state of mutual induction" exists between the two cores when a current is passing through the coils, the opposite poles of the cores being adjacent. This construction does not produce an actual electromagnet; but the cores being parallel and the windings connected mutual induction produces the same effect in a slighter degree. The secondary coils are separated from the primary by the usual insulation and are wound and connected in series, two of their terminals being directly connected.

A contact-breaker or vibrator, comprising an armature-plate *j*, supported by suitable 75 vibrator-springs *k* *k'*, and a standard *l*, carrying a contact-screw *m*, is secured outside the casing to the end of same in such a manner that the face of the armature-plate is adjacent to the ends of the cores *g* and *g'*. The 80 armature-plate *j* is preferably made of one piece of thin soft iron. I do not confine myself to a one-piece armature-plate, however, inasmuch as the same may be of laminated structure or constructed with soft-iron heads 85 adjacent to the core ends connected by a piece of spring metal or strap-iron. It is practicable to support the armature upon a single spring secured to the center of the plate, if desired. My preferred construction, a thin 90 light-weight spring-mounted armature-plate extending from core to core of two independently-mounted induction-coils, produces a vibrator which is capable of a very high rate of speed, resulting in intense sparks of extremely quick repetition, which result is difficult to attain with spark-coils of the ordinary construction. For use with explosive-engines 95 in automobiles or where the apparatus is subjected to jar a heavy iron vibrating armature 100

would become unreliable by reason of its inertia and its responding to shock. At every jolt of the vehicle it would jar and get out of rhythm, while with the armature and the short stiff springs shown in the drawings in connection with the double coils sparks pass with uniform regularity and immediately and surely when required.

Referring to the diagram Fig. 5, the electrical connections are as follows: The primary terminal *o* is connected, through binding-post *p*, with battery *q*, thence through binding-post *r* with the armature-spring *k*. The other primary terminals being directly connected at *s*, the primary circuit is completed by the connection *t* to the standard *l* through the contact-screw *m* and the armature-plate *j*. The condenser *c* is connected as a shunt across the interrupter through binding-post *r* and standard *l*. The secondary coils are connected in series at *u*, as described, the other terminals leading to the binding-posts *v* and *w*, from which wires may be run to the sparking electrodes in the cylinder of an explosive-engine.

25 By constructing jump-spark apparatus in the manner described I am enabled to produce a device of considerably less bulk, the two coils taking less space than one coil of the ordinary type, because less wire is used. It has been found in practice that it is not necessary to use with two coils of this description more than half the amount of wire required for one made in the ordinary manner. As wire is one of the costly elements in induction-coil construction, this advantage is of some importance.

Various modifications in the details of construction may be made without departing from the principle and intended scope of my invention.

I claim—

1. In sparking apparatus the combination with a source of current, of induction-coils having separate cores, and primary and secondary windings and a contact-breaker comprising an adjustable contact-piece and a vibrating armature arranged between ends of the cores and said contact-piece, said primary

coils being connected with said source of current, contact-piece and armature and with each other in series, substantially as described. 50

2. In a jump-spark apparatus, a pair of induction-coils having their primary windings connected in series, a separate core for each coil, and a contact-breaker provided with an armature-plate having its face adjacent to the ends of the cores, substantially as described. 55

3. In a jump-spark apparatus, a pair of electrically-connected induction-coils mounted parallel to each other, a separate core for each coil, and a contact-breaker provided with an armature-plate of substantially uniform magnetic permeability throughout, substantially as described. 60

4. In a jump-spark apparatus, the combination of a plurality of secondary windings each of which is located about a separate primary winding, an independent core for each of the primary windings, and a contact-breaker provided with an armature-plate supported by a spring at each end and having its face adjacent to the ends of the cores, substantially as described. 65

5. In an electric circuit, a pair of induction-coils mounted parallel to each other and having separate cores, a contact-breaker provided with a spring-mounted armature having its face adjacent to ends of the cores, and a condenser shunted across the contact-breaker, substantially as described. 70 75

6. In a jump-spark apparatus, the combination with a suitable casing, of a pair of parallel induction-coils having separate cores and a condenser in the casing embedded in and separated by a body of non-conducting material, and a contact-breaker for the coils provided with a spring-mounted armature having its face adjacent to the ends of the cores, substantially as described. 80 85

In witness whereof I hereto affix my signature in presence of two witnesses.

HERMAN C. MUELLER.
